WELT CEMENTING AND APPLYING
MACHINEJohn R. Oliver, Beverly, Mass., assignor to United
Shoe Machinery Corporation, Flemington,
N. J., a corporation of New Jersey

Application March 24, 1945, Serial No. 584,537

14 Claims. (Cl. 12—51)

This invention relates to welt cementing and applying machines and is herein illustrated as embodied in a machine for adhesively attaching a welt strip to an outstanding flange of a shoe adjacent to the welt crease.

A machine for applying welts to shoe flanges is illustrated in Letters Patent of the United States No. 2,345,002, granted March 28, 1944, upon my application, but, in that machine, while means are provided for supporting and presenting a welt strip, it is necessary to bring the shoe into co-operative relationship thereto manually. Furthermore, with the arrangement there shown, the trimming of the inseam material forming the shoe flange must be carried out as a separate operation, as must the application of cement to this welt strip or to the shoe.

An object of the present invention is to provide an improved machine of this type by means of which the related operations may be more economically carried out.

In accordance with this object, shoe-feeding mechanism is provided in predetermined relation to a welt-strip-feeding mechanism and, as herein illustrated, this shoe-feeding mechanism grips the inseam material forming the flange of the shoe, the arrangement being such that the welt and the shoe are fed forwardly at corresponding or at identical rates.

A feature of the invention resides in the combination of a device for trimming away the superfluous material of the inseam flange with such an improved mechanism.

In accordance with another feature of the invention, there is associated with the work-feeding devices an adhesive-applying mechanism by means of which a suitable cement may be applied to the edge of the welt strip or to the shoe flange or to both, just prior to their contact as the attaching operation proceeds. In its illustrated form, this adhesive-applying mechanism comprises a nozzle having one or more outlet openings adjacent to the edge of the welt and/or to the inclined shoe flange and it is contemplated that this nozzle may be supplied with cement, such as a heated thermoplastic material, which is delivered under pressure to the nozzle.

These and other features of this invention will best be understood from a consideration of the following specification taken in connection with the accompanying drawings, in which

Fig. 1 is a front elevation of the machine;

Fig. 2 is a side elevation with parts broken away and in section;

Fig. 3 is an enlarged view looking down on the

top of the welt-strip-presenting and cutting-off mechanisms;

Fig. 4 is a side elevation thereof with parts broken away and in section;

Fig. 5 is a vertical section through the welt-presenting mechanism;

Fig. 6 is a fragmentary view on a much larger scale, substantially in horizontal section through the flange of a portion of a shoe and through an extruding nozzle and looking down on the top of the welt-strip-presenting device;

Fig. 7 is a front elevation of the work-feeding parts and with the nozzle shown in vertical section; and

Fig. 8 is an enlarged detail in elevation showing the feed rolls for the shoe flange and the relation of the applying nozzle thereto.

In order to present a strip of welting, there is provided a mechanism similar to that disclosed in the above-mentioned patent, including an upper strip-gripping disk 10 (Fig. 5) having a flange 12 overhanging the hub of the disk, said flange providing a horizontal face engaging the upper face of a welt strip W and cooperating with a lower disk 14 engaging the under face of said strip. At the inner edge of the flange is an abutment against which the flat edge of the welt rests so that the strip is held horizontally with its beveled edge exposed. This mechanism is mounted in a subframe 20 secured by screws 22 (Fig. 2) to a horizontal plate 24 forming an integral part of the main frame 26 and extending transversely of the front face of this frame. On this subframe 20 is an upstanding sleeve 28 (Fig. 5) in which there is journaled a depending stud 30 forming an integral part of the upper disk 10. Around the sleeve 28 is a hemispherical cup 32 forming part of the subframe 20 and receiving a spherical projection 34 on the under face of the lower disk 14. An opening at the center of this spherical projection 34 is larger than the sleeve 28 so that the lower disk 14 may tilt slightly under the influence of a drag-finger 36 (Fig. 4) pulled downwardly by a spring 38 surrounding a headed stud 40 attached to that finger. The shank 42 of the drag-finger 36 is square, as indicated in Fig. 3, to prevent the drag-finger from rotating in the enlarged guide portion 44 of the subframe 20 in which it slides, and it will be seen from Fig. 4 that the under surface of the drag-finger 36 is rounded to reduce its friction with the upper surface of the disk 14. It will be noted, also, that the point of engagement of said drag-finger with the lower disk 14 is offset slightly beyond a vertical plane through the axis of said

disk and normal to the front face of the frame 26 and, as a result, the point of greatest pressure upon the welt strip is diametrically opposite this drag-finger and hence at about the position indicated by the arrow C in Fig. 3.

To drive the disks 10 and 14 which present the welt strip, there is provided a gear train comprising a pinion 50 (Fig. 5) which is integral with the top disk 10, a large gear 52 (Fig. 3) journaled on a stud 53 held by a setscrew 54, a pair of gears 56, 58 (Fig. 4) on another stud in the subframe, and a bevel gear 60. This bevel gear 60 is at the lower end of a shaft 62 journaled at that end in the subframe and at its upper end in a bracket 64 (Fig. 2) detachably mounted upon another bracket 66 which is secured to a portion of the main frame 26.

Power to drive the machine, and in particular the welt-feeding mechanism, is received from a driving belt 70 (Fig. 1) and delivered to a pulley 72 on a shaft 74 journaled in the frame of the machine. On this shaft, is a large gear 76 meshing with a gear 78 (Fig. 2) on a shaft 80 also journaled in the frame of the machine and having near its mid-portion a helical gear 82. Meshed with this gear 82 is another helical gear 84 rotatable upon the upright shaft 62 and adapted to be joined thereto by a clutch 86 operated by a bell crank 88 which is pivoted at 90 in the bracket 64 and is adapted to be raised to close the clutch upon operation of a rod 92 joined to one end of a lever 94 the other end of which is connected to a treadle rod 96. When the operator depresses the treadle connected to the rod 96, the lever 94 will be rocked on its shaft 95, thus raising the rod 92 to close the clutch yieldably under the action of a spring 98 surrounding that rod.

In order that the strip may be severed at the end of a particular operation, a cutting-off knife 100 (Fig. 4) has been provided which is mounted on a slide 102 guided in a box 104 which is integral with a portion 106 (Fig. 2) of the bracket 66. This knife slide 102 is intended to be actuated by the operator when desired and, to that end, is provided with a rack which meshes with a segment 108 pivoted in the box. The segment is joined by a link 110 (Fig. 4) to the upper end of an arm 112 forming part of a bell crank, the lower arm of which is shown at 114 in Fig. 2. Attached to this bell-crank arm is another treadle rod 116. Depression of the treadle will be effective to cause a forward movement (to the left in Fig. 4) of the knife blade 100 to sever the weltting and, for this purpose, the upper disk 10 is provided with a series of radial slots 118. It is essential, therefore, that one of these slots shall be aligned with the knife blade and, to that end, the double gear 56, 58 is provided with a star wheel 120. The upright arm 112, with its upper end turned inwardly over the gear 52, carries a yieldably mounted pin 122 (Fig. 3) with a beveled end which fits in one of the notches of the star wheel. When the pin strikes the star wheel, it aligns the slots in the disk 10 with the knife before the movement of the latter into one of those slots.

To assist the operator in presenting a shoe, having an outturned flange F (Fig. 4) adjacent to the inseam and, hence, the welt crease, in inclined position for the attachment of the strip of welt thereto, a shoe-feeding mechanism has been provided comprising a freely rotatable lower disk 124 rotatably carried by a lug 126 (Fig. 4) held between upwardly extending arms 128 form-

ing a part of the subframe 20. These arms are joined by a cross brace 130 (Figs. 3 and 7). Associated with the lug 126 are ball bearings 132 which are enclosed in a casing 134. The under side of the lower disk 124 is beveled to provide clearance for the cutting-off knife 100 while the upper face thereof serves to support the outwardly extending flange F formed by the material of the shoe on a last L, such as the upper 136, the lining 138 and a middle sole 140 overlying, in an inverted shoe, an insole 142 (Fig. 8). The upper and lining are thread-lasted to the middle sole by means of stitches 144.

Gripping the upper face of the composite flange F against the disk 124 at an angle corresponding to the angle of the beveled edge of the weltting is a driven feed roll 146 rotatable upon a stud 148 (Fig. 8) which is integral with the depending lower end 150 of an arm 152 capable of a slight rocking movement upon a cross pin 154 (Fig. 2) in the main frame. In this arm 152 is journaled a shaft 156 having at its lower end a gear 158 meshing with a pinion 160 (Fig. 4) which forms a part of the feed roll 146. On the upper end of the arm is a helical gear 162 meshing with the helical gear 82 on the driven shaft 80. The lower end of the arm 152 is guided between extensions 164 of the upright arms 128. This arm 152 is connected by a link 166 (Fig. 2) with a pivotally mounted cover 168 swinging on a pin 170 at the top of the frame and having a rearwardly extending portion 172 which has a limited movement between stop screws 174 and 176 and is normally pressed downwardly by a spring 178 in a direction to lift the upper feed roll 146. After the flange F of the shoe has been inserted between the disk 124 and the feed roll 146, a depression of the treadle connected to the treadle rod 96 will be effective to bring the feed rolls together because the upper end of the rod 92 passes through an eye 180 on the arm 172 and the rod has fixed to it a flange 182 beneath this eye. Lock nuts 184 on the upper end of the rod rest against the upper side of the eye 180 and cause the cover to swing with up and down movements of the rod.

Although it will be understood that the welt strip W may have its beveled edge 190 (Fig. 6) precoated with cement which is tacky and thus is ready to attach the strip to the shoe flange F, it is found desirable, in some instances at least, to apply a coating of cement directly to the welt strip and preferably also to the shoe flange just before they are brought together as the welt strip is guided and fed by the disks 10, 14 and as the shoe is guided and fed by the engagement of the driven roll 146 and the supporting disk 124 with the flange F of the shoe. In order that the attaching cement may set quickly, it will be found convenient to utilize a thermoplastic adhesive, such as one of the vinyl resins, and to extrude it through a heated nozzle under pressure. To this end, the machine is provided with a nozzle 200 (Fig. 1) supported on the subframe 20 by means of screws 202 (Fig. 7) and having outlet openings 204 and 206 (Fig. 6) for coating respectively the shoe flange and the welt strip. Beyond these outlets, grooves 208 are provided to facilitate the outward passage of the cement and to prevent the latter from being wiped off the work as the two portions thereof are moved forward with the assistance of their feeding means. These outlet openings 204 and 206 are supplied through a passage 210 to which there is joined a flexible hose 212 to which an adhesive may be

supplied in any desired fashion. One suitable mechanism for supplying such an adhesive in liquid form and under pressure is illustrated in Letters Patent of the United States No. 2,301,202, granted November 10, 1942, upon the application of Paul H. Dixon, wherein there is shown a heated receptacle and pump the outlet of which is operator-controlled by a valve. A rod 213 (Fig. 2) attached to the treadle-operated lever 94 is arranged to open the pump valve (not shown) as the work feeds are started. In order to prevent hardening of the material in the nozzle itself, the latter is provided with a heating unit 214. It will be noted, furthermore, from Figs. 7 and 8 that the nozzle casting is provided with a guideway 215 through which the welt strip W is led as it is brought up to the feed disks 10 and 14.

Immediately after the attachment of the welt strip to the shoe and while the flange F is still gripped between the feed rolls 146 and the disk 124, a large part of the upstanding portion of the flange is trimmed from the shoe by means of a bell-shaped knife 220 (Figs. 1 and 2) journaled in a slide 222 which is adjustable along a grooved carrier 224 by means of a hand wheel 226. This adjustment serves to compensate for the wear of the knife 220 as it is sharpened.

This knife is driven by means of a train of gears 228, 230 and 232, the latter of which meshes with the gear 78 irrespective of the adjusted position of the knife-carrying slide 222. An arrangement of this sort is more fully illustrated and described in Letters Patent of the United States No. 1,974,487, granted September 25, 1934, upon the application of Andrew Eppler, and, as in that patent, means for sharpening the cutting knife is provided in the form of a grinder 234 to which power may be supplied by means of a belt 236 passing at its lower end over a pulley 238 and adapted to be driven by a belt 240 from a suitable source of power whenever an associated clutch is closed by movement of a hand lever 242.

In the use of the machine, a welt strip W from a suitable source of supply will be introduced in the guideway 216 of the nozzle and pressed into the notch formed between the flanges of the disks 10 and 14 in such a position that the square edge of the welt is against the bottom of that groove, and the beveled edge 190 thereof is on the side toward the operator. It will be understood that the disks grip the welt as they come together adjacent to the shoe and then release it again as they move away from the shoe under the action of the spring-pressed drag-finger 36 which bears on the lower disk 14. A shoe having a flange F ready for the attachment thereto of the welt will be presented to the machine with its flange between the feed rolls 124, 146. Assuming, then, that the machine is in operation and that a suitable supply of cement is delivered to the hose 212, the operator will depress the treadle connected to the treadle rod 96, thus closing the clutch 86 to drive the feed for the welt strip and lowering the upper feed roll 146 to grip the shoe flange. At the same time, the rod 213 will cause the adhesive to be supplied under pressure to the nozzle 200. The two parts to be joined adhesive-ly will be carried along at corresponding rates, and cement will be extruded upon the shoe flange and upon the beveled face of the welt. As the work is fed, the operator will press the shoe against the machine to bring the shoe flange into a close contact with the beveled edge of the welt

as it is supported by the disks 10 and 14 and will turn the shoe to bring its whole periphery into engagement with that strip while, at the same time, the flange will be trimmed by the knife 220.

5 At the end of the operation, the operator will release the treadle connected to the rod 96 and will depress the treadle connected to the rod 116 to cause a forward movement of the knife blade 100 to sever the welt strip at a point where it is gripped by the disks 10 and 14. In so doing, it will be assured that the knife will pass through one of the radial clutches 118 in the upper disk because of the action of the pointed wedge 122 upon the star wheel 120 associated with the drive for the upper disk. The pump valve will prevent more cement from being forced out until another shoe is presented thereto.

Having thus described my invention, what I claim as new and desire to secure by Letters Patent of the United States is:

1. In a machine for attaching strip welting to the flange of a shoe, means for feeding the shoe past an operating point, and welt-strip-feeding means for presenting a portion of a welt strip 25 in a predetermined relation to said feeding means.

2. In a machine for attaching strip welting to the flange of a shoe, feeding means gripping the flange to feed the shoe past an operating point, and welt-strip-feeding means for presenting a portion of a welt strip in a predetermined relation to said feeding means.

3. In a machine for attaching strip welting to the flange of a shoe, feeding means gripping the flange to feed the shoe past an operating point, welt-strip-feeding means for presenting a portion of a welt strip in a predetermined relation to said shoe-feeding means, and means for trimming away a portion of the material forming the flange as it leaves said feeding mechanism.

4. In a machine for attaching a strip welting to the flange of a shoe, separable feed rolls gripping flanged upper material adjacent to the inseam and arranged thus to feed the shoe past an operating point, and a welt-strip-feeding mechanism gripping the upper and lower faces of a welt strip and supporting a portion of it in predetermined relation to said feed rolls.

5. In a machine for adhesively attaching strip welting to the flange of a shoe, separable feed rolls arranged to grip flanged upper material adjacent to the inseam and arranged thus to feed the shoe past an operating point, a welt-strip-feeding mechanism gripping the upper and lower faces of a strip and supporting a portion of it in predetermined relation to said feed rolls, and means adjacent to the discharge side of said feed rolls for trimming away a portion of the material gripped by said rolls, thus leaving a projecting flange adjacent to the inseam to which a welt has been adhesively attached.

6. In a machine for adhesively attaching strip welting to the flange of a shoe, shoe-guiding means, welt-strip-guiding and gripping means presenting an edge portion of the welt strip adjacent to said guiding means, and means for applying cement to said edge portion just before the flange of the shoe is brought into contact therewith.

7. In a machine for adhesively attaching strip welting to the flange of a shoe, shoe-guiding means, strip-feeding means for gripping a welt and presenting an edge portion thereof to a shoe flange positioned by said guiding means, and means for applying cement to the coacting sur-

faces of the welt and the shoe flange at a point where the two are approaching each other.

8. In a machine for adhesively attaching strip welting to the flange of a shoe, shoe-guiding means; rotary means for feeding a welt strip curved to present a portion of it to the flange of the shoe, and a cement-applying nozzle adjacent to a curved portion of said strip-presenting means and through which cement may be extruded upon the welt strip and the shoe flange to attach them as they are brought together.

9. In a machine for adhesively attaching strip welting having a beveled edge to the inclined flange of a shoe, shoe-feeding means for gripping said flange and presenting it at an inclined relation, welt-strip-feeding means arranged to present the beveled portion of a strip to the correspondingly inclined flange of the shoe, and means for extruding cement upon at least one of said shoe parts just prior to their mutual contact.

10. In a machine for adhesively attaching a welt strip having a beveled edge to the inclined flange of a shoe, welt-strip-guiding and feeding means comprising a substantially horizontally disposed face contacting with the upper surface of a welt strip, means arranged for contact with the lower face of the strip to grip it and feed it, and flange-gripping and feeding devices arranged at an inclination to the horizontal, thereby to hold the shoe flange at an angle corresponding to the angle of the bevel of the edge of the welting.

11. In a machine for progressively attaching beveled-edge strip welting to the outturned flange of a shoe adjacent to the welt crease, means for gripping a section of the welt strip and rigidly holding it with its beveled edge in a position for attachment adjacent to the welt crease, means adjacent to the first-named means arranged to grip the opposite sides of a shoe flange and to advance it at a rate corresponding to the advancement of the welt strip, and means for ap-

plying an adhesive to the beveled edge of the welt strip just prior to its engagement with the welt crease.

12. In a machine for progressively attaching beveled-edge strip welting to the outturned flange of a shoe adjacent to the welt crease, a disk having a peripheral groove therein frictionally to receive and engage the opposite sides of a welt strip, said disk being rotatable to advance a length of welting into a position to be laid into the welt crease, means adjacent to the disk arranged to grip the opposite sides of the flange and to advance it at a rate corresponding to the advancement of the welt strip, and means for applying an adhesive to the beveled edge of the welt strip just prior to its engagement with the welt crease.

13. In a machine for adhesively attaching strip welting to a flange on a shoe, separable feed rolls arranged to grip flanged upper material to feed the shoe past an operating point, a welt-strip-feeding mechanism for guiding a strip to a point of attachment to the shoe, means for applying cement to at least one of the parts to be attached prior to contact between them, and means for trimming away a portion of the material forming the flange as it leaves said feeding mechanism.

14. In a machine for adhesively attaching strip welting having a beveled edge to the inclined flange of a shoe, separable feed rolls gripping said flange and presenting it in inclined relation, rotary means for feeding a welt strip along a curve tangent to the flange held by the feed rolls for attachment at that point, a cement-applying nozzle adjacent to a curved portion of said rotary means for the application of cement to the coacting surfaces of the welt and the shoe flange at a point where the two are approaching each other, and a trimmer adjacent to the delivery side of said feed rolls for removing a portion of the flange outside of its point of attachment to the welt strip.

JOHN R. OLIVER.
